CARDIO-AXIOGRAPH INSTRUMENT

William Candib, Schenectady, N.Y., assignor to Electro Medical Research Associates, Schenectady, N.Y., a corporation of New York

Filed Nov. 24, 1959, Ser. No. 58,454

Term of patent 3½ years

(Cl. D83—1)

Fig. 1

Fig. 2

Fig. 3

FIG. 1 is a front perspective view of a cardio-axiograph instrument, showing my new design.

FIG. 2 is a side elevational view on a much smaller scale; and

FIG. 3 is a rear elevational view on the same scale as FIG. 2.

I claim:

The ornamental design for a cardio-axiograph instrument, as shown.
